METHOD AND APPARATUS FOR MOUNTING FILAMENTS

Filed June 1, 1936

UNITED STATES PATENT OFFICE

2,114,844

METHOD AND APPARATUS FOR MOUNTING
FILAMENTSPaul W. Krause, Youngstown, Ohio, assignor to
General Electric Company, a corporation of
New York

Application June 1, 1936, Serial No. 82,759,

12 Claims. (Cl. 176—4)

My invention relates to the manufacture of incandescent lamps and similar devices which comprise filaments, and more particularly to methods and apparatus for mounting concentrated filaments which are required to be definitely positioned. One application of my invention is to the mounting of filaments for projection and automobile lamps. In projection lamps, or the like, which cooperate with reflectors and lenses in producing a well-defined light beam, it is necessary that the filament be positioned very accurately with reference thereto in order to produce the desired beam and to eliminate stray or uncontrolled light.

Irregularities in lamp construction which cause the filament to be located out of position are usually compensated for by separate means attached either to the lamp or to the reflector, and it is the principal object of my invention to provide a method and apparatus for accurately mounting the filament so that the need for these means is lessened. Another object of my invention is to reduce the difficulty with which the filament is mounted due to its small size and frailty. Another object of my invention is to increase the economy and speed with which the filament is mounted.

According to my invention, I provide a plane surface on which a plurality of filaments are piled and an instrument for manually shifting said filaments about in order to separate one from the rest. A form is provided on the plane surface adjacent means for holding the stem and leading-in wires and the filament is pushed, through use of the instrument, against the form to locate it properly with respect to said leading-in wires. Electrodes are also provided to weld the filament to the leading-in wires while both are retained in this position. I prefer to use an instrument and a form of such shape as to confine all of the filament excepting its ends in a restricted space so that there is no possibility of the filament's being mounted out of position. For instance, with a straight filament coil the plane surface provides the bottom side of the confining space; the instrument, the top, one end, and one side thereof; and the form the other end and the other side thereof.

Other objects and advantages of my invention will appear from the detailed description which follows of species thereof and from the accompanying drawing.

In the drawing Fig. 1 is a perspective view of a device constituting one embodiment of my invention; Fig. 2 is a plan view on an enlarged scale of

a portion of said embodiment; Fig. 3 is a side elevation of the portion of the embodiment shown in Fig. 2 with the lamp stem broken away along line 3—3; Fig. 4 is a plan view of a similar portion of another embodiment of my invention, and Fig. 5 is a side elevation thereof with the lamp stem broken away along line 6—6 of Fig. 4.

In the embodiment of my invention shown in Figs. 1, 2, and 3, a quantity of lamp filaments 10 are placed on the plane surface of the tray 11 and the lamp stems 12 on which the filaments 10 are to be mounted are placed on the holder 13 with the ends of the leading-in wires 14, 15, and 16 resting on the electrode 17. The filaments 10 in this particular instance, each comprises a quite tightly wound coil having straight ends extending laterally outward from the coil and from the top and bottom-most portions thereof. The stems 12 in this instance are each of tipless construction with an exhaust tube 18 extending therefrom which is rested in the V grooves in the holder 13 and with leading-in wires 14, 15, and 16 having laterally bent and aligned ends which are rested on the end of electrode 17. The tray 11, the holder 13 and the electrode 17 are mounted on the frame 19 of the device, the electrode 17 being located in a groove in said frame 19 as shown in Fig. 2 and being clamped into position by the blocks 20, 21 and bolts 22, 23. A large magnifying glass may also be mounted adjustably to the frame 19 to enable the operator to see more clearly and to function more effectively.

The operator of this device first places with the left hand the stem 12 into the position already indicated, with the ends of the leading-in wires 14, 15, and 16 spaced from the edge of the electrode 17 nearest the tray 11, as shown in Fig. 2. The operator with the right hand takes the instrument or tool 24 and separates one filament 10 from the rest on the tray 11. The separated filament 10 is then caught in the groove or opening 25 in the under near side of the tool 24 and with the bent end of said tool 24 resting on the tray 11, is pushed along the top plane surface thereof and onto the plane surface of the plate 26. The opening 25 in the tool 24 is substantially the same size as the filament coil and is so constructed as to prevent injury to said filament. To bring the filament 10 into the mounting position it is shifted on the plate 26 until the straight ends straddle the stop plate 27 and take position above and below the bent end portions of leading-in wires 14 and 15 respectively, (note: in Fig. 2 the stem 12 is turned 180° from the position re-

ferred to, but for this portion of the description leading-in wires 16 and 15 may be referred to equally well), and the side and end of the coiled portion lies against the stop plate 27 and stop finger 28 respectively. The stop plate 27 and the stop finger 28 constitute a form for holding the filament in position. The stem 12 may have to be adjusted slightly to help the straight ends of the filament 10 fall into position without injury.

10 The angularity of the end of the electrode 17 tilts the stem 12 so that the leading-in wires 14 and 15 engage the filament ends at their respective elevations since the thickness of said leading-in wires is less than the difference in elevation between the filament ends.

With the stem 12 held by the left hand and the holder 13 and the filament 10 held in position by the tool 24 in the right hand, the electrodes 29 and 30 are caused to be moved down through movement of a foot pedal (not shown) until the filament 10 and the leading-in wires 14 and 15 are engaged and welded together. The electrodes 29 and 30 are attached to the levers 31 and 32 respectively by the bolt 33, and block 34 and bolt 35 respectively, and are operated about the shaft 36 by arm 37. The arm 37 engages the levers 31 and 32 through springs 38 and 39 respectively and stop pin 40 and is fastened to shaft 36 which is operated by the foot pedal through mechanism 30 (not shown), rod 41 and arm 42. The electrodes 17, 29, and 30 are so arranged that electrode 29 engages and welds the lamp parts together first before the electrode 30 engages and welds said lamp parts. The excess movement of arm 37 after electrode 29 engages the lamp parts is taken up by spring 38 and by spring 39 after the electrode 30 engages said lamp parts. The electrodes 17, 29, and 30 are connected through the flexible cables 43, 44, and 45 to the welding circuit (not shown) which controls the timing and amount of current used.

A second filament 10 is attached to the leading-in wires 15 and 16 of the stem 12 with the same set up. The second filament is attached after the stem 12 is taken out and replaced after being turned 180° on its longitudinal axis and takes a position on the opposite side of the axis corresponding to that of the first filament. In this position of the stem 12 the first filament 10 lies in the groove 46 in the plate 26 and the stem 12 is adjusted so that the coiled portion of the filament 10 engages the stop finger 28 and the bottom of the groove 46. The first filament 10 also rests on the block 47 in said groove which causes the filaments 10-10 or leading-in wires 14, 15, and 16 to be bent if they are not properly positioned as the second filament is welded on. The operations in attaching the second filament to the leading-in wires 15 and 16 are exactly the same as those used in attaching the first filament and are not described further.

The embodiment of my device shown in Figs. 4 and 5 is provided for mounting V-shaped coiled filaments 50 and in the instance shown is employed to mount two V-shaped filaments, one above the other, on the stem 51 (only partially shown). The device differs from the other device only in the parts which engage the filaments 50 and which are shown in Figs. 4 and 5. The 70 filaments 50 lie on the tray 11 as before but the stem 51 rests in the holder with the leading-in wires 52 and 53 resting on the electrode 54 in the position shown. A filament 50 is selected from those on the tray 11 and, by manipulation 75 of the tool 55, is caught in the V groove 56 in

the lower face of the end thereof. The filament 50 is pushed and slid along the plane surface of the tray 11 and plate or block 57 into engagement with the V-shaped projection or form 58 of the block 57 which locates it with reference to the leading-in wires 52 and 53 as shown. The V notch 59 in the tool allows the operator to see whether the filament 50 is properly located in the V groove 56 of the tool 55.

The ends of the filament 50 take positions 10 above and below the leading-in wires 52 and 53 respectively since one end extends from the top and the other end extends from the bottom of the filament coil. The filament 50 is now welded to the leading-in wires 52 and 53 by electrodes 15 (not shown) similar to those in Fig. 1 which are brought down into engagement therewith. During these operations a leading-in wire 60 (Fig. 5) which is located below leading-in wire 53 and the support wire 61 which is located below leading-in wire 52 and is attached thereto, lie in the aperture 62 in electrode 54.

A second filament 50 is attached to the leading-in and support wires 60 and 61 in a similar manner after the stem 51 is turned over. The 25 stem 51 is removed, turned 180° and replaced with the ends of the leading-in and support wires 60 and 61 placed in the desired position on the electrode 54 and the first filament 50 and the leading-in wires 52 and 53 located in the aperture 30 62 in said electrode 54. The support wire 61 functions as another leading-in wire and is fastened to leading-in wire 52.

What I claim as new and desire to secure by Letters Patent of the United States is:

1. The method of mounting a filament on a stem having a pair of leading-in wires extending therefrom which comprises supporting said stem in a definite relation to a plane surface, sliding a filament on said plane surface to a definite position with reference to said stem and said leading-in wires and attaching said filament to the leading-in wires in said position.

2. The method of mounting a filament on a stem having a pair of leading-in wires extending therefrom which comprises supporting said stem in a definite relation to a plane surface, catching a filament in an opening in the bottom of a tool rested on said plane surface, sliding said filament on said plane surface to a definite position with reference to said stem and said leading-in wires by manipulation of said tool and attaching said filament to the leading-in wires in said position.

3. The method of mounting a filament on a stem having a pair of leading-in wires extending therefrom which comprises supporting said stem in a definite relation to a plane surface and a form thereon, sliding a filament on said plane surface and into engagement with said form so that it is positioned with reference to said stem and said leading-in wires and attaching said filament to the leading-in wires in said position.

4. The method of mounting a pair of filaments on a stem having a plurality of leading-in wires extending therefrom which comprises supporting said stem with a pair of said leading-in wires in a definite relation to a plane surface, sliding a filament on said plane surface to a definite position with reference to said pair of leading-in wires, attaching said filament to said leading-in wires in said position, adjusting said stem to bring a second pair of leading-in wires into a definite position with reference to said plane surface, sliding a second filament on said plane surface to a definite position with reference to

said second pair of leading-in wires and in attaching said second filament to said second pair of leading-in wires in said position.

5. An apparatus for mounting filaments on stems having leading-in wires extending therefrom comprising a holder for a stem, a tray mounted adjacent said holder for supporting a plurality of filaments, a form mounted at the edge of said tray and in a definite relation to said holder, a tool for separating one filament from the remainder on said tray and for sliding it thereon into engagement with the form and means for attaching said filament to the leading-in wires in this position.

6. An apparatus for mounting filaments on stems having leading-in wires extending therefrom comprising a holder for a stem, a tray mounted adjacent said holder for supporting a plurality of filaments, a tool having a portion adapted to rest on the tray and having an opening in said portion adapted to hold a filament, for separating one filament on the tray from the remainder and for sliding said filament into a definite position with reference to the leading-in wires, and means for attaching said filament to the leading-in wires.

7. An apparatus for mounting filaments on stems having leading-in wires extending therefrom comprising a holder for a stem, a tray mounted adjacent said holder for supporting a plurality of filaments, a form mounted at the edge of said tray and in a definite relation to said holder, a tool having a portion adapted to rest on the tray and having an opening in said portion adapted to hold a filament, for separating one filament on the tray from the remainder and for sliding said filament against the form, and means for attaching said filament to the leading-in wires in this position.

8. An apparatus for mounting filaments on stems having leading-in wires extending therefrom comprising a holder for a stem, a tray mounted adjacent said holder for supporting a plurality of filaments, an electrode mounted adjacent the edge of said tray and having the top surface thereof inclined and partially above and below the surface of the tray for supporting the ends of leading-in wires extending from the stem, a tool for separating one filament from the remainder on said tray and for sliding it thereon to the edge adjacent the electrode and in engagement with said leading-in wires, an electrode mounted above the first and means for moving said electrode down onto the filament and leading-in wires to weld them together.

9. An apparatus for mounting filaments on stems having leading-in wires extending therefrom comprising a holder for a stem, a tray mounted adjacent said holder for supporting a plurality of filaments, a form mounted at the

edge of said tray and in a definite relation to said holder, a tool for separating one filament from the remainder on said tray and for sliding it thereon into engagement with the form, means for attaching said filament to the leading-in wires in this position and a groove in said tray for holding and positioning the filament when the stem is adjusted to another position in the holder in which a second filament is attached to leading-in wires extending therefrom.

10

10. Apparatus for mounting filaments on stems having leading-in wires extending therefrom comprising a substantially flat horizontally disposed tray for supporting a plurality of coiled filaments having outwardly extending end portions, a form mounted adjacent to the edge of said tray, a stem holder mounted adjacent to said edge of said tray for holding a stem with portions of a pair of its leading-in wires in definite relation to said form, means for engaging one of the filaments on said tray and sliding it thereon into engagement with said form, and means for attaching said filament ends to said portions of said leading-in wires.

15

11. Apparatus for mounting filaments on stems having leading-in wires extending therefrom comprising a substantially flat horizontally disposed tray for supporting a plurality of coiled filaments having outwardly extending end portions, a form mounted adjacent to the edge of said tray, a stem holder mounted adjacent to said edge of said tray for holding a stem with portions of a pair of its leading-in wires in definite relation to said form, a tool having a groove therein of the same shape as the mid-portions of said filaments for engaging one of the filaments on said tray and sliding it thereon into engagement with said form, and means for attaching said filament ends to said portions of said leading-in wires.

20

40. 12. Apparatus for mounting filaments on stems having leading-in wires extending therefrom comprising a substantially flat horizontally disposed tray for supporting a plurality of coiled filaments having outwardly extending end portions, an electrode mounted adjacent to the edge of said tray, a form mounted adjacent to the edge of said tray and said electrode, a stem holder mounted adjacent to said edge of said tray for holding a stem with portions of a pair of its leading-in wires on said electrode in definite relation to said form, means for engaging one of the filaments on said tray and sliding it thereon into engagement with said form, an electrode located above said first-mentioned electrode, and means for moving said second-mentioned electrode toward said first-mentioned electrode to weld the said ends of said filament and the said portions of the leading-in wires together.
